(57) **CLAIM**

The ornamental design for a camping stove, as shown and described.

DESCRIPTION

FIG. 1 is a top, right, perspective view of a camping stove showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, right, perspective view of a camping stove showing a second embodiment of our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines are to disclose the environment related to the claimed design, and are not considered to be part of the claimed design
